Patented July 11, 1922.

UNITED STATES PATENT OFFICE.

CLARENCE E. BEACH, OF BINGHAMTON, NEW YORK, ASSIGNOR, BY MESNE ASSIGNMENTS, TO THE GAMEWELL FIRE ALARM TELEGRAPH COMPANY, A CORPORATION OF NEW YORK.

SIGNALING MECHANISM.

1,422,523.

Specification of Letters Patent.

Patented July 11, 1922.

Original application filed October 12, 1914, Serial No. 866,322. Divided and this application filed June 18, 1917. Serial No. 175,309.

To all whom it may concern:

Be it known that I, CLARENCE E. BEACH, a citizen of the United States, residing at Binghamton, in the county of Broome and 5 State of New York, have invented certain new and useful Improvements in Signaling Mechanism, of which the following is a specification.

This application is a division of my Patent No. 1,240,811, dated September 25, 1917.

This invention relates to signaling mechanisms adapted for use in a signaling system and particularly to a municipal police signaling system in which provision is made 15 for the transmission of both telephonic and telegraphic signals, and has specific reference to signaling mechanism which is adapted to be adjusted for the control of independent alarm devices upon the transmission of different classes of signals, without interfering with the simultaneous transmission of telephonic or telegraphic signals.

The object of this invention is to provide a relay or signal controlling mechanism 25 adapted to be so associated with the signaling circuit that upon the transmission of one class of signals over the circuit the relay will be adjusted for the control of one set of alarm mechanism and upon the transmission of another class of signals over the circuit the relay will be adjusted for the control of a separate set of alarm mechanism.

The means whereby this object is attained 35 is in the provision of a relay of specific construction so connected to the signal circuit that the direction of current flow over the signal circuit and a common return conductor, such as the ground, will adjust the 40 relay for the control of the desired alarm mechanism.

The alarm controlling relay mechanisms are of novel form, and each comprises two electromagnets, a terminal of one magnet 45 being connected to one side of the circuit, and a terminal of the other magnet being connected to the other side of said circuit.

The remaining terminals of the magnets are connected to a common return conductor, 50 as for instance, to the ground.

An armature structure for these magnets is so mounted in relation thereto that the energy of one of said magnets will be applied to the portion of said structure associated with the other of said magnets, during 55

a portion of the movement of said armature, at a leverage which is substantially greater than the leverage at which the energy of such magnet will be applied to said portion during the remainder of the movement 60 of said armature.

A contact arm is carried by the armature structure whereby circuit connections may be established between either of two sets of contacts, and alarm mechanism is associated 65 with each relay, as for instance, a lamp controlled by one contact, and a bell controlled by the other contact.

For signaling systems employing so-called open circuit primary batteries, and in which it is therefore desirable that there should not be a continuous current drain on such batteries, all of the features of this invention may be employed by providing two normally disconnected common return conductors, as for instance, the ground, and a third 70 wire, and connecting one of the magnets of each alarm controlling relay between one side of the circuit and one of the common return conductors, as for instance, the third 75 wire, and connecting the other magnet of such relay between the other side of the circuit, and the other common return conductor, as for instance, the ground, keeping the two common return conductors normally 80 disconnected from each other, and connecting the two common return conductors through a condenser, if necessary to secure 85 absence of noise in the telephone circuit, and providing facilities for directly connecting such conductors by a switch whenever it is desired to cause the operation of the 90 alarm relays.

For signaling systems in which it is not necessary to maintain an electrical balance 95 between the circuit conductors and the common return conductor, by connecting one magnet of each alarm relay between one circuit conductor and the common return conductor, and connecting the other magnet of 100 each relay between the other circuit conductor and the common return conductor, provision may be made for open circuit battery operation by employing a retractile spring, or a permanent magnet, in place of 105 one of the electromagnets in the relay, and connecting the other magnet between one of the circuit conductors and the common return conductor, and arranging the relay so that:—when the armature is in complete- 110

ly retracted position both alarm mechanism circuits will be open; when in partially retracted position, one of the alarm mechanism circuits will be closed; and when in 5 fully attracted position the other of the alarm mechanism circuits will be closed,— and thus all other features of this invention may be employed.

Figure 1 is a plan view of a relay embodying the features of my invention.

Fig. 2 is a sectional view of the relay of Fig. 1, taken on the line 2—2.

Fig. 3 is a sectional view of the relay shown in Fig. 1, taken on the line 3—3.

15 Fig. 4 is a modified form of the relay shown in Fig. 1 adapted for response to changes in current strength.

Fig. 5 is an elevation of a different form of relay mechanism embodying features of 20 this invention.

Fig. 6 shows a typical form of circuit illustrating the use of the relays of Figs. 1, 2, 3 and 5.

25 Fig. 7 shows a typical form of circuit illustrating the use of the relay of Fig. 4.

Referring to Figures 1, 2 and 3, which show in detail the construction of a relay embodying my invention, it is seen that the relay magnets 71 and 72 are mounted on a 30 suitable base and have secured to their poles, a non-magnetic plate 81, through suitable openings of which the poles project.

The armature structure 82 is mounted 35 upon the plate 81 and has the inclined ends 83 and 84 so formed with relation to the magnets 71 and 72 that when the portion of the armature between the bends adjacent to said inclined ends is resting upon 40 the plate 81, the end 83 will incline away from but extend across the poles of the magnet 71, and the end 84 will incline away from but extend across the poles of the magnet 72.

45 The locating pins 85, secured to the plate 81, pass through suitable openings in the armature structure 82, and are arranged to permit such movement of said armature structure as will bring one or the other of the inclined ends substantially parallel to and against the poles of its associated magnet. When the armature structure 82 moves, in response to the attraction of its end 83 toward the magnet 71, until said end 50 is substantially parallel to and against the poles of said magnet, said armature structure rocks on the bend adjacent to said end 83, and hence during such movement said bend acts as a fulcrum for said structure, and when the end 84 is moved substantially 55 parallel to and against the poles of the magnet 72, the bend adjacent to said end 84 acts as a fulcrum for said structure.

60 It will therefore be seen that two fulcrums are so provided that this armature

structure is adapted to rock upon either fulcrum, and that when so rocked the pull of the magnet upon one of the inclined ends of said structure will have a great advantage over the pull of the other magnet upon 75 the other end of said structure. It will further be seen that when neither magnet is energized, the armature structure will be held upon both fulcrums by the force of gravity, and that the magnets may therefore be energized and de-energized without disturbing said armature structure, so long as the pull of one magnet does not exceed the pull of the other magnet by the difference in advantage which exists when the 80 armature structure is resting upon but one fulcrum, and that whenever the pull of either magnet exceeds said difference, such magnet will draw toward its poles the inclined end of the armature structure associated therewith and move the other inclined end away from the poles of the other magnet.

It will further be seen that whenever the 90 pull of the two magnets becomes substantially equal, after the armature structure has been rocked upon one fulcrum as just described, the superior advantage of the magnet which is acting upon the end of the armature structure which is furthest from 95 its supporting fulcrum, will cause the armature structure to rock upon said fulcrum to the position where it rests upon both fulcrums, where its movement will be arrested through the substantially equal pull 100 of the two magnets, as already explained.

If the relay is to be subjected to such shocks or movement as might cause the armature structure 82 to become disengaged from the pins 85, a guard 86 should be 105 provided to keep such structure in engagement with said pins.

The contact arm 87 is mounted upon, but 110 insulated from, the armature structure 82, and carries at its free end the movable contact 88 in such position that, when the end 83 is substantially parallel to and against the poles of magnet 71, said bar 88 will connect the fixed terminals 77 and 78, and that 115 when the end 84 is in like relation to the magnet 72, said bar will connect the fixed terminals 79 and 80.

These parts therefore constitute a circuit controller and on account of governing the operative condition of separate alarm devices may be called alarm controlling mechanism.

The relay of Figs. 1, 2, 3 and 5 is adapted for use in various classes of signaling and other circuits; a typical circuit arrangement 125 for the utilization of such relays being shown by Fig. 6, in which a suitable current source A is associated with circuit-condition-changing-means comprising the switch B whereby one terminal or the other of such 130

source may be connected with the ground. The circuit conductors 101 and 102 lead from respective terminals of the source A to multiple connections between said circuit conductors each serially including the magnets 71 and 72 of such a relay and having a ground connection therefrom applied between such magnets.

Under normal conditions, there is current flow from the source through conductor 101 and through the magnets 71 and 72 of each of the current paths which connect the conductor 101 with the conductor 102; thence through the conductor 102 to the other terminal of the source A.

Inasmuch as the magnets 71 and 82 of each of the respective relays will be traversed by the same current, the energization of both magnets of each relay will be substantially equal. If, now, the switch B is raised to the one of its co-engaging contacts to which an extension of the conductor 101 is connected, a current path will be established through the ground which will short-circuit the magnets 71 of each of the relays, whereupon the armature of said relays will move in response to the pull of their respective associated magnets 72, and the contacts of such relays will be suitably operated incident to such movement. If the switch B is moved downwardly into engagement with the contact to which an extension of the conductor 102 is connected, the magnets 72 of the respective relays will be short-circuited with corresponding results.

Referring to Fig. 4, it will be noted that the armature structure 82' there shown is mounted in a manner similar to that shown in Figs. 1, 2 and 3, and that the electromagnet 72' is mounted in suitable relation to the inclined end 84' of said structure, while means is provided, for moving said end 84' away from said magnet 72', consisting of a spring 92 applied to the inclined end 83' of said armature structure.

A movable contact 88' is carried by the contact arm 87, moving with the armature structure 82', and the fixed contacts 79' and 80' are so mounted in the path of said movable contact 88' that when the inclined end 84' of armature structure 82' is moved substantially parallel to and against the poles of electromagnet 72'', said contacts 79' and 80' will be connected by the contact 88'.

The fixed contacts 77' and 78' are so mounted, in the path of the movable contact 88', that when the armature structure 82' is resting upon both of its fulcrums, said contacts 77' and 78' will be connected by the contact 88', but when said armature structure 82' is in the position where either of its inclined ends are substantially parallel to the plate 81', said contact 88' will not connect said contacts 77' and 78'.

The strength of the spring 92 is such when

the magnet 72'' is de-energized the armature structure will rock upon the fulcrum adjacent to its inclined end 83' until said end is moved substantially parallel to and against the plate 81', and so that when said magnet 72'' is suitably energized, the pull of said magnet 72'' upon the inclined end 84' of said structure 82' will cause said structure to first rock upon the fulcrum adjacent to its inclined end 83' until it rests upon both fulcrums, and to thereafter rock upon the fulcrum adjacent to its inclined end 84' until such inclined end is substantially parallel to and against the poles of said magnet 72''.

Owing to the fact that the pull of the magnet 72'' operates at much greater advantage, against spring 92, when the armature structure 82' is rocking upon the fulcrum adjacent to its end 83', than when said structure is rocking upon the fulcrum adjacent to its end 84', it is evident that a much weaker current flow through the magnet 72'' will move said armature structure, from the position where its end 83' is substantially parallel to and against the plate 81', to the position where said structure rests upon both of its fulcrums, than the current required to move said armature structure, from the position where it rests upon both of its fulcrums, to the position where its inclined end 84' is substantially parallel to and against the poles of the magnet 72''.

From the foregoing it will be seen that the relay of Fig. 4 is particularly suited for utilization where it is desired that respective conditionings of responsive mechanism shall not be altered because of changes in energizing current strength within certain clearly defined ranges, but shall be altered whenever such current varies from a strength within one to a strength within another of such ranges.

A typical circuit arrangement for utilizing this form of relay is shown by Fig. 7, in which a suitable current source A' is associated with circuit-condition-changing means comprising the switch B' whereby either one terminal or an intermediate potential tap from said one source may be connected to the ground. The circuit conductors 101 and 102 lead from respective terminals of the source A', and connections each serially including the magnet 72'' of a relay such as that shown in Fig. 4, are provided between the conductor 101 and the ground.

Under normal conditions the magnets 72'' are deenergized and the contact 88' is positioned to the left of the contact 78' (as viewed in Fig. 4). If, now, the switch B' is raised to the one of its co-engaging contacts to which the intermediate tap from the source A' is connected, a current path will be established through the ground which will be subjected to less than all of

the electromotive force of said source. Due to the resultant current flow through each of the magnets 72" the structures 82' of such relays will thereupon rock upon the fulcrums nearest the ends 83' thereof until said structure rests upon both fulcrums; whereupon the pull of the magnet 72" will be insufficient to continue the movement of said structure, as the spring 92 will thereafter 10 be acting at a much greater advantage than during the preceding movement of said structure. If the switch B' is moved downwardly into engagement with the contact to which an extension of the conductor 102 is connected, the magnets 72" of the respective 15 relays will be sufficiently energized to cause the structure 82' to rock around the fulcrum adjacent to its inclined end 84' until the contact 88' is brought into engagement 20 with the contact 80'.

Fig. 5 shows a form of relay so embodying certain features of this invention, that said relay may be used in the place of the relay shown in Figs. 1, 2, and 3. Or by substituting a spring (such as the spring 92 shown in Fig. 4) or a permanent magnet for one of the electromagnets shown in Fig. 5, the relay shown in said figure may be used in place of the relay shown on Fig. 4.

In constructing the relay shown in Fig. 5, electromagnets 71''' and 72''' are suitably mounted, and an armature structure is provided therefor, consisting of the inclined ends 83" and 84", pivoted at 203 and 204, and carrying the armatures 201 and 202, respectively.

The springs 205 and 206 are connected to the inclined ends 83" and 84", respectively, in such manner as to tend to move said ends 40 toward the magnets 71''' and 72'''.

The strut plate 81" passes between the inclined ends 83" and 84", and is provided with the locating pins 85' extending through suitable openings in the inclined ends 83" 45 and 84".

As the transmission of motion, from the inclined end 83" to the inclined end 84", through the plate 81" is similar to the corresponding transmission between inclined end 50 83 and inclined end 84 in Figs. 1, 2 and 3, the points of engagement between the inclined ends 83" and 84" and the plate 81" are, for want of a better term, herein called fulcrums.

The fulcrums are so positioned as to hold the inclined ends 83" and 84" a suitable distance from their cooperating magnets.

When the armature structure moves, in response to the attraction of the inclined 60 ends 84", toward the magnet 72''' until the armature 202 is substantially parallel to and against the poles of said magnet, said inclined end 84" rocks on the corner of the plate 81" adjacent to the free end of 65 said inclined end 84", and the inclined end

82" rocks on the corner of the plate 81" adjacent to the pivoted end of said inclined end 83", and hence during said movement said corners act as a fulcrum for said structure, and when the armature structure is moved, in response to the attraction of the inclined end 83", toward the magnet 71''' until the armature 201 is substantially parallel to and against the poles of said magnet, the corner of the plate 81" adjacent to the free end of said inclined end 83", and the corner of said plate 81" adjacent to the pivoted end of the end 84", act as a fulcrum for said structure.

It will therefore be seen that two fulcrums 80 are so provided that this armature structure is adapted to rock upon either fulcrum, and that when so rocked the pull of a magnet upon one of the inclined ends of said structure will have a great advantage over the pull 85 of the other magnet upon the other end of said structure. It will further be seen that when neither magnet is energized, the armature structure will be held upon both fulcrums by the action of the springs 205 and 206, and that the magnets may therefore be energized and de-energized without disturbing said armature structure, so long as the pull of one magnet does not exceed the pull 95 of the other magnet by the difference in advantage which exists when the armature structure is resting upon but one fulcrum, and that whenever the pull of either magnet exceeds said difference, such magnet will draw toward its poles the end of the structure associated therewith and move the other end away from the poles of the other magnet.

It will further be seen that whenever the pull of the two magnets becomes substantially equal, after the armature structure has 105 been rocked upon one fulcrum, as just described, the superior advantage of the magnet which is acting upon the end whose supporting fulcrum is nearest to its pivot, will cause said armature structure to rock upon 110 said fulcrum to the position where both fulcrums become effective, where the movement of said structure will be arrested through the substantially equal pull of both magnets and both springs, as already explained.

Having now fully described this invention, what I claim and desire to secure by Letters Patent of the United States is:

1. In a signaling mechanism, an electromagnet, an armature structure therefor movable into a plurality of different positions, and supporting means for said armature structure arranged to provide a plurality of predetermined definite leverages between said armature structure and electro-magnet 125 corresponding to predetermined positions assumed by said armature structure.

2. In a signaling mechanism, two electromagnets, an armature structure for said magnets, two fulcrums about either of which 130

said structure may rock, a contact arm moving with said structure, a connecting bar carried at the free end of said contact arm, and fixed contacts in the path of said connecting bar.

5 3. In a signaling mechanism, two electromagnets, an armature structure for said magnets, two fulcrums about either of which said structure may rock, and suitable means for maintaining said structure in proper relation to said magnets and to said fulcrums.

10 4. In a signaling mechanism, two electromagnets, an armature structure for said magnets, two fulcrums upon which said structure is mounted, said structure arranged to rock upon either fulcrum, and locating pins mounted in suitable relation to each fulcrum for maintaining the armature structure in proper relation thereto.

15 5. In a signaling mechanism, two electromagnets, an armature structure for said magnets, two fulcrums upon which said structure is mounted, said structure arranged to rock upon either fulcrum, locating pins mounted 20 in suitable relation to each fulcrum for maintaining the armature structure in

proper relation thereto, and a guard for preventing disengagement of the armature structure from said pins.

6. In a signaling mechanism, an armature structure movable into a plurality of different positions, a mounting means therefor, two governing means for said structure arranged to move it in opposite directions, said mounting means arranged to provide a plurality of different definite leverages between said armature structure and governing means corresponding to predetermined positions assumed by said structure.

10 7. A relay structure comprising an armature, two fulcrums on either of which said armature may rock, and means including an electromagnet adapted to rock it about either of said fulcrums.

15 8. A relay structure having an armature, two spaced fulcrums on either of which said armatures may rock and both arranged to support said armature in a stable predetermined position, and means including an electro-magnet adapted to rock said armature 25 about either of said fulcrums.

C. E. BEACH.
